GROMMET

Daniel F. Shepherd, United States Army,
Richmond, Va.

Application August 26, 1941, Serial No. 408,336

1 Claim. (Cl. 102—1)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a grommet and means for securing the same to protect the rotating bands of shells.

Modern artillery projectiles are conventionally provided with rotating bands the purpose of which is to seal the bore around the projectile against the escape of gas and to engage the rifling of the bore to transmit rotation to the shell. It will be readily apparent that, if the rotating band or bands are accidentally deformed prior to firing, such deformation will have a serious effect upon the accuracy of the flight of the projectile and tend to greatly increase erosion of the gun bore.

Accordingly it is the object of this invention to produce an improved means for protecting projectile rotating bands, which means can be economically manufactured and conveniently applied and removed.

A further object is to produce a protective member which can be readily applied to the protection of shaft bearing surfaces, pipe threads and the like.

The specific nature of the invention as well as other objects and advantages thereof will clearly appear from a description of a preferred embodiment as shown in the accompanying drawing in which:

Figure 1 is an elevation, partly in section of the preferred embodiment of my invention;

Figure 2 is an end elevation of the device shown in Figure 1.

Figure 3 is a view similar to Figure 1 showing a modified form of securing means.

Figure 4 is a fragmentary end elevation of the device of Figure 3.

Figure 5 is a fragmentary cross section showing the details of the cushioning member illustrated in Figs. 1 and 3.

Figures 6 and 7 are fragmentary cross sections showing modifications of the cushioning member as applied to other forms of rotating bands.

Referring to the drawing by characters of reference the grommet comprises a flexible split band 10 of steel or other material having a cushioning member 11 secured therein and provided with resilient securing means comprising the spring members 12 and 13. In the preferred embodiment as shown in Figs. 1 and 2 the spring member 12 is provided at one end with a hook 14 engaging the loop 15 formed in the surface of

the band 10 and at the other end with an eye 16 to engage the member 13. The member 13 is preferably formed by twisting a single piece of spring wire upon itself to form a handle portion 5 having a hook 18 at the doubled end of the wire and diverging leg wires forming a semi-circular section 19 terminating in end sections 20 to be inserted in loops 21 formed in the surface of the band 10. A similar loop 22 is provided to engage the hook member 18.

In the employment of the grommet described above the band 10 is opened sufficiently to permit it to be slipped over the projectile body 8 to a position in which the cushioning member 11 15 engages the rotating bands 9. The handle portion of the member 13 is engaged in the eye 16 of the member 12 and the member 13 drawn into a position in which the hook 18 is engaged in the loop 22. As the member 13 is preferably formed 20 of highly resilient material such as spring steel, the "give" in the semi-circular section 19 will provide tension to keep the grommet securely engaged with the rotating bands. Further, such a construction will be inherently self-adjustable 25 to accommodate itself to minor variations in the length of the split band. The grommet may be readily released by springing the handle laterally far enough to allow disengagement of the hook 18 from the loop 22.

30 In the modified form of my invention shown in Figs. 3 and 4 the securing means comprises a member 32 substantially similar to that shown as 12 in Figure 1 and a member 33 which is a modified form of that shown as 13 in Fig. 1. In

35 this form of the invention a straight section of spring wire 23 is engaged in a loop 24 at one extremity of the band 10. The ends of the wire are brought together to form a semi-circular portion 25 and a handle portion of double wire.

40 A hook 26 may be provided in the band 10 under which the end of the arm may be engaged. This modification of the invention may be employed in the same manner as that described above in connection with Figures 1 and 2.

45 In Figure 5 a detail cross section illustrates the form of the cushioning member indicated generally as 11 on Figures 1 to 4. This cushioning member is shown as applied to a projectile body 8 having a pair of rotating bands 9. A wide strip 50 of cotton webbing 21 may have secured to it by sewing or other methods a plurality of narrower strips 28 to engage the projectile body between and at the ends of the rotating bands. The cushioning band is then secured to the split band 55 10 by riveting or by any other convenient means.

Figures 6 and 7 show modified forms of cushioning bands built up by securing together a plurality of laminar strips to obtain the contours necessary for engaging projectiles having rotating bands of different sectional form.

Obviously the cushioning member may be molded as a unit from rubber or any suitable plastic material to the exact form needed to fit the rotating bands after which it may be secured to the split band in any desired manner.

I claim:

A grommet for protecting the outer surface of cylindrical metal objects comprising a split ring having cushioning means secured to the inner

perimeter thereof, a lever of flexible material formed with a central operating arm and laterally diverging arms having pivotal connection with one end of the ring substantially coextensive with the width of the ring, a link loosely connected with the lever at the juncture of the diverging arms and the operating arm, the opposite end of the link being loosely connected with the central portion of the other end of the ring, and means carried by the lever end of the ring into and out of engagement with which the lever arm is flexed to lock or unlock the lever.

DANIEL F. SHEPHERD.
